UNITED STATES PATENT OFFICE.

AUGUSTE REMY, JEAN RENAUD, JEAN DELORT, AND FRANCIS DEBREBANT, OF BEZU ST. ELOI, FRANCE.

SOUND-RECORDING AND SOUND-REPRODUCING MACHINE.

Application filed May 19, 1923, Serial No. 640,081, and in France June 1, 1922.

This invention relates to a sound-recording and sound-reproducing machine of the kind in which the stylus track, or sound grooves is on a disc or circular record. The machine according to the invention greatly increases the recording capacity per unit area of records hitherto known. The machine moreover is designed to reproduce sound also from the usual type of record now on the market.

The sound-recording method and apparatus according to this invention render it possible to produce records bearing a far larger number of sound grooves than records hitherto known. The said apparatus is characterized in that the turntable which hitherto was moved at a constant angular speed is moved, according to the invention, at a constant linear speed so that the sound grooves are uniform in size whatever be the point of the record on which they are located. The turntable and the record are moreover bodily propelled in a horizontal plane so that fresh portions of the record are constantly brought at constant speed within reach of the stylus recording the sound waves and fresh portions of the turntable are constantly brought within reach of the friction wheel.

The mechanism whereby the machine according to the invention is made instantly ready for reproducing sound from a record manufactured according to the hitherto known methods, is of a very simple character and is fully described hereunder.

A constructional example of the machine according to the invention is illustrated in the accompanying drawings in which—

Figure 1 is a side elevation of the said machine with the casing removed.

Figure 2 is a plan.

Figure 3 illustrates the mechanism whereby the driving friction wheel is held in proper contact with the turntable.

Figure 4 shows the rack and elements pertaining thereto in elevation and plan.

Figure 5 is a section on line A—A of Figure 2 and purports to show a portion of the mechanism.

Figure 6 is a partial view of the tone arm and of the device provided for locking it in playing position.

Figure 7 is a plan view of the recess pro-

vided in the tone arm for the above-mentioned setting.

Figure 8 is a large scale view of the locking or setting device proper.

Figure 9 is a view, on a greatly reduced scale, of the top plate or deck of the machine.

The machine according to the invention is enclosed in the usual way, in a casing made of any desired material and provided with adornments of any kind. Neither the casing nor the driving motor, which may likewise be of any desired character, is shown in the drawings, but the shaft 19 indicated in Figs. 1 and 2 may be assumed to be the motor shaft. Two frame plates 1 are secured to the casing by means of flanges formed by bending the lower edges of the plates at right angles; the said plates are rigidly connected to one another by two tie-rods or tie-tubes 2. The plates are additionally tied together by two cylindrical bars 3 secured to the upper portion of the said plates, and these two bars 3 are intended to conjointly carry and guide a slide 5 which in turn carries the turntable 4 (shown dotted) and the mechanism for actuating and propelling the same. One of the sides of the slide 5 completely surrounds one of the bars 3 and moves thereon. The lower face of the slide is fitted with a supporting frame 6 integral with or rigidly secured to the said slide. The said frame carries the spindle 8 on which the turntable 4 and its support 7 are mounted, a suitable portion of the said spindle being cut to form a worm 7 in engagement with a suitably dimensioned worm wheel 9 rigidly secured to a toothed pin 10 rolling on and meshing with a rack 11 movably mounted on a spindle 12 and controlled by a spring 35. The said rack is thrown in and out of engagement with the pinion 10 by means of an externally mounted and manually operated crank-handle 13 provided with a suitable snap mechanism engaging catches or the like provided on a plate fixed to the outer wall of the casing, for the purpose of placing the rack in the desired position straightaway and without resorting to trial movements. The rack is thrown in and out of engagement with the pinion according as sound is to be reproduced from a record of the known

type or of the type produced in accordance with the invention. To this end, a striker arm 14 is provided, which co-operates with a finger 15 secured to the rack and projecting therefrom.

A cam 16 has its hub secured to and near one end of the rack spindle and has for its purpose to coact with a lateral pin 37 fixed to an arm 36 on a subsequently-described support 22 in bringing a driving friction wheel 20, hereafter referred to, out of contact with the turntable at the moment the rack is moved out of engagement with the pinion, the engagement of the parts 16 and 37 having the effect of rocking the support in a direction to lower wheel 20. One end of the previously mentioned helical spring 35 is secured by a screw V¹ to the cam, the said spring being intended to smooth out any jerk or shock arising from a faulty initial contact between the rack and the pinion, and to establish ultimately the correct contact, when the rack is raised into its operative position. The rack spindle is moreover provided with a small arm 17 which, in cooperation with another arm 18, throws the motor out of action when necessary, as hereinafter explained.

The turntable 4 is rotated by the friction wheel 20 which is constituted by a disc 21 made of rubber or leather, or of any other suitable material, clamped between two circular cheeks. The friction wheel is rotatably mounted on the upper end of the support 22 mentioned above, which support has the shape of a bell-crank and is pivoted at its apex on the motor shaft 19 and adapted to oscillate about the same. The motor drives the friction wheel 20 through the medium of two pulleys 23 over which passes a belt 24. The friction wheel 20 and the upper pulley are of course rigidly mounted on a common shaft and rotate together. The friction wheel 20 is constantly held in contact with the turntable 4 by a spring 25, one of the ends of which is fastened to the lower end or other suitable point of the support 22. The movement of the friction wheel in one direction is limited by a stop 26 integral with or secured to the frame plate 1; the support 22 comes to rest against the said stop.

The tone arm 28 is supported on a bracket 27 (Figure 6) and is adapted to be moved as customary, in two planes at right angles to one another. The bracket is fitted with a device whereby the tone arm is locked in the correct starting position, with the stylus at the proper starting point on the record without requiring trials. Referring to Figures 6 and 8, this device comprises a cylindrical plunger 29 abutting on a small piston 31 adapted to slide in the casing of the said device and provided with a pointed stem 31^a adapted to engage a hole or recess

30 provided in the tone arm. The plunger 29 is normally held in the raised position by a helical spring located in the casing of the device.

The deck plate 32 of the machine is provided with a slot 33 affording passage of the driving roller 20 therethrough and passage and displacement of the spindle carrying the turntable 4 supported on the disc 8. The deck has moreover a gauge or level 34 whereby the machine may be placed in a truly horizontal position; it has furthermore markings or graduations indicating the speeds at which the records are to be rotated and the points at which they are to be placed, according as sound is to be produced from records of the known type or from those produced in accordance with the invention.

The machine according to the invention works as follows for sound-recording purposes:

The friction wheel 20 is held by the spring 25 constantly in contact with the lower face and substantially near the edge of the turntable 4 carrying the blank record. The rack 11 is in the raised or operative position (as in Figure 1) and is therefore in engagement with the pinion 10. The turntable is actuated by the motor shaft 19 through the medium of the belt 24, the pulleys 23 and the friction wheel 20, and in turn actuates the worm 7, the worm-wheel 9, and pinion 10 and the rack 11. The sound-recording or sound-reproducing stylus is in its operative position. The turntable and the record supported thereon are thus rotated about their common axis and also linearly propelled so that fresh portions of the surface of the turntable, nearer and nearer the centre thereof, are successively brought within reach of the friction wheel 20.

The angular velocity of the latter being constant, that of the turntable is gradually increased in proportion as the centre of the turntable moves nearer the friction wheel. The stylus is always vertically above the friction wheel 20 whatever the position of the latter relatively to the turntable, due to the fact that the tone arm is locked by the device 29-31, and that the turn table moves linearly with relation to the tone arm.

The movement of the various elements is the same for reproducing sound from a record produced according to the present invention. The record is placed in its correct position with the aid of the graduations or marks provided on the deck 32. The operator thereafter depresses the plunger 29, thus causing the pointed end 31^a to engage the recess 30 of the tone-arm 28 which is now lowered by hand, together with the stylus, into the correct starting position on the record without having to find the said position by trial.

As stated above, this machine renders it possible to reproduce sound from records as now on the market. To this end, the last-mentioned type of record is placed in the correct relative position to the graduation or mark provided on the deck 32. The rack 11 is lowered into its inoperative position by operating the crank handle 13 and bringing its index or hand opposite or in engagement with the desired catch or other detent means provided externally on the cabinet wall. The pinion 10 is now out of engagement with the rack so that the turntable is no longer linearly propelled but is of course rotated about its own axis. The friction wheel 20 may be brought into contact straightaway with any desired point on the lower face of the turntable for the purpose of rotating the latter at the desired angular speed.

The machine according to the invention therefore renders it possible to produce sound from records made in accordance with the said invention and with records as now on the market. The machine may be set for producing sound from one or the other of these records by a single operation of the crank handle whereby the rack is thrown into or out of engagement with the pinion.

The helical spring 35 constantly pulls the rack towards the pinion for the purpose of rapidly and smoothly bringing these two elements into engagement in case the teeth of the one do not immediately drop in the gaps of the other; this arrangement protects the teeth of the said elements from being damaged.

The motor is automatically thrown out of action when the rack is unmeshed from pinion 10 after the playing of the record is finished, owing to the fact that this movement of the rack brings its arm 17 into the path of the arm 18 on the motor shaft, so that the latter arm, which rotates constantly with the motor shaft, is thus brought into contact with arm 17, whereby the further rotation of said shaft is stopped. The slide is thereafter moved backwards manually and with ease so that the turntable is brought to its initial or other position ready to be actuated anew for reproducing sound from the following record.

The angular velocity of the record is read from the marks or graduations provided on the deck of the machine, the said angular velocity being independent of the speed of the motor and being imparted to the turntable at a rate in accordance with the relative position of the friction wheel and of the said turntable.

We claim:

1. Sound-recording and reproducing apparatus, comprising a turntable; mechanism for rotating it; and mechanism for imparting a linear movement to the turntable dur-

ing its rotation, and embodying a pinion, driving means therefor, a pivotally-mounted rack along which the pinion is adapted to travel, and means for rocking said rack about its longitudinal axis to bring it into 70 or out of mesh with said pinion.

2. Apparatus according to claim 1, in which a rotatable spindle is provided whereon the rack has a loose, pivotal mounting; and in which the rack-rocking means comprise an arm on the rack and an arm on the spindle for engaging the first-named arm when the spindle is rotated. 75

3. In sound-recording and reproducing apparatus, the combination of a turntable; a 80 driving wheel movable into and out of engagement with the turntable; means for rotating said wheel; means for imparting a linear movement to the turntable during its rotation; and a common means for disengaging the wheel and positively terminating its rotation, and for interrupting the linear movement of the turntable. 85

4. In sound-recording and reproducing apparatus, the combination of a turntable; a 90 driving wheel engageable therewith; a driving shaft; a pulley fixed thereto; a pulley belted to the first pulley and to which the driving wheel is connected to be driven thereby; a rocking support carrying the second pulley; a spindle; and a cam on said spindle engageable with said support to rock the same and thereby move the driving wheel out of engagement with the turntable. 95

5. In sound-recording and reproducing apparatus, the combination of a turntable; a driving wheel engageable therewith; a driving shaft; a pulley fixed thereto; a pulley belted to the first pulley and to which the driving wheel is connected to be driven thereby; a rocking support carrying the second pulley; a spindle; and separate devices on said spindle for coaction, respectively, with said support and said shaft to rock the support and thereby move the driving wheel out of engagement with the turntable, and to positively terminate the rotation of said shaft. 100 105 110

6. In sound-recording and reproducing apparatus, the combination of a turntable; a driving wheel engageable therewith; a driving shaft; a pulley fixed thereto; a pulley belted to the first pulley and to which the driving wheel is connected to be driven thereby; a rocking support carrying the second pulley; a spindle; and a device on said spindle cooperative with said support to rock the same and thereby move the driving wheel out of engagement with the turntable. 115 120 125

7. In sound-recording and reproducing apparatus, the combination of a turntable; a driving wheel engageable therewith; a driving shaft; a pulley fixed thereto; a pulley belted to the first pulley and to which the driving wheel is connected to be driven there- 130

by; a rocking support carrying the second pulley; a spindle; means for rocking said support to move the driving wheel out of engagement with the turntable; and means operated by said spindle for positively terminating the rotation of the driving shaft.

8. In sound-recording and reproducing apparatus, the combination of a turntable; a driving wheel engageable therewith; a driving shaft; a pulley fixed thereto; a pulley belted to the first pulley and to which the driving wheel is connected to be driven thereby; a rocking support carrying the second pulley; a spindle; and a pair of separate projections fixed to the spindle, one projection cooperative with said support to rock the same and thereby move the driving wheel out of engagement with the turntable, and the other projection cooperative with the driving shaft to positively terminate its rotation.

9. Apparatus according to claim 8, in which the driving shaft is provided with a lateral arm directly engageable by the last-named projection on the spindle to arrest the rotation of said shaft.

10. In sound-recording and reproducing apparatus, the combination of a turntable; a driving wheel therefor; a rocking carrier for said wheel; resilient means connected with said carrier for normally maintaining said wheel engaged with the turntable; mechanism for imparting a linear movement to said turntable and including a rack-and-pinion device; resilient means normally maintaining the rack and pinion engaged; means for rocking said carrier in a direction to disengage the driving wheel from the turntable; and means for disengaging the rack from the pinion.

11. In sound-recording and reproducing apparatus, the combination of a turntable; a driving wheel therefor; a rocking carrier for said wheel; resilient means connected with said carrier for normally maintaining said wheel engaged with the turntable; mechanism for imparting a linear movement to said turntable and including a rack-and-pinion device; resilient means normally maintaining the rack and pinion engaged; means for rocking said carrier in a direction to disengage the driving wheel from the turntable; and means for disengaging the rack from

the pinion; and a single operating element common to both disengaging means.

12. In sound-recording and reproducing apparatus, the combination of a turntable; a driving wheel therefor; a rocking carrier for said wheel mounted on a pivot to swing about the same; resilient means connected with said carrier for moving it in one direction about its pivot to maintain said wheel normally engaged with the turntable; mechanism for imparting a linear movement to said turntable during its rotation; means for interrupting the action of the movement-imparting mechanism at will; and a member carried by one element of said mechanism for engaging and swinging said carrier in the opposite direction about its pivot so as to withdraw the driving wheel from the turntable when an interruption of the action of said mechanism takes place.

13. In sound-recording and reproducing apparatus, the combination of a turntable; a driving wheel therefor; a rocking carrier for said wheel mounted on a pivot to swing about the same; resilient means connected with said carrier for moving it in one direction about its pivot to maintain said wheel normally engaged with the turntable; mechanism for imparting a linear movement to said turntable during its rotation and including a rack-and-pinion device; means for disengaging the rack from the pinion; and means carried by the rack for engaging and swinging said carrier in the opposite direction about its pivot, during the movement of disengagement of said rack from the pinion, so as to withdraw the driving wheel from the turntable.

14. Apparatus according to claim 13, in which the carrier-rocking means comprises a cam on the rack, and a projection on the carrier for coaction therewith.

15. Apparatus according to claim 13, in which the carrier-rocking means comprises a cam on the rack, and a projection on the carrier having a lateral pin for engagement by said cam.

In testimony whereof we have signed our names to this specification.
